UNITED STATES PATENT OFFICE.

OTTO VON SCHROETTER, OF KRUPPAMÜHLE, UPPER SILESIA, GERMANY.

EXPLOSIVE.

No. 908,149.

Specification of Letters Patent.

Patented Dec. 29, 1908.

Application filed May 9, 1907. Serial No. 372,686.

To all whom it may concern:

Be it known that I, OTTO FREIHERR VON SCHROETTER, a subject of the King of Prussia, residing at Kruppamühle, Upper Silesia, 5 German Empire, have invented a certain new and Improved Explosive, of which the following is a specification.

When gunpowder and its substitutes, as well as many other explosives can be fired 10 by direct ignition, the so-called high explosives, like guncotton and nitroglycerin cannot be fired directly. Gun-cotton, nitroglycerin, dynamite, picric acid and the like, require mercuric fulminate as a detonator. 15 Gun-cotton, however, can only be detonated by a mercuric fulminate cap when it is dry, not when it is moist throughout. Much less can the detonation be effected by means of other explosives; even such explosive substances as nitroglycerin, dynamite, gelatin-dynamite and the like fail when the gun-cotton charge is saturated with water.

The discovery by Brown that wet charges could be detonated by means of dry gun-cotton was at that time of far reaching importance for the applicability of gun-cotton, particularly for purposes of war.

The drawing represents a side view, partly in section, of my improved explosive. 30 According to the present invention, wet gun-cotton can be detonated in any quantity, with certainty and far more advantageously than by means of dry gun-cotton, by nitro-compounds of the aromatic series. Substances of this kind prove particularly suitable for conveying the detonation from the cap to the wet charge of gun-cotton not only

with absolute certainty but with enhanced effect. The action of a wet gun-cotton charge can be considerably heightened by 40 suitable selection of the agent for transferring the detonation. A torpedo charge *a*, of wet gun cotton is recessed to contain an intermediate charge *b*, of a nitro compound of the aromatic series, such as hexanitrodi-phenylamin, trinitrotoluol, etc., in which the mercuric fulminate cap *c*, is embedded. Thus the cap detonates the wet gun cotton through the intermediate charge of the nitro compound. 50

A further advantage in practice attends the transference of the detonation by one of the aforesaid materials instead of by dry gun-cotton, in that these materials are effective in cases in which dry gun-cotton fails 55 as a priming, as for instance when it has become wet. This is more particularly of practical importance when charges must remain long under water before they are fired.

What I claim and desire to secure by Letters Patent of the United States is:

An explosive consisting of a charge of wet gun cotton, a fulminate, and a detonating charge of a nitro compound of the aromatic series intermediate the wet gun cotton and 65 fulminate, substantially as specified.

In witness whereof, I have hereunto signed my name in the presence of two subscribing witnesses.

OTTO VON SCHROETTER.
